ORIENTING BUTTON-ATTACHING
MACHINEFrederick H. Peterson, Watertown, Conn., assign-
or to The Patent Button Company, Waterbury,
Conn., a corporation of Connecticut

Application June 23, 1939, Serial No. 280,859

1 Claim. (Cl. 218—6)

My invention relates to new and useful improvements in orienting mechanism for button-attaching machines, and is a continuation in part of an application filed by me on December 12, 1938, Serial Number 245,278, for Orienting button-attaching machine.

In the application aforementioned, the hopper, from which the oriented buttons pass down to the attaching station, was rotated in a step-by-step movement in certain synchronism with the action of the attaching plunger, and the buttons, as they were carried up the side of the rotating hopper, would pass, when they properly aligned themselves, through certain grooves in the hopper and then into the chute, where they traveled in their certain rotated position to the attaching station.

Due to the fact that the buttons can only pass from the hopper in one oriented position, it happened at times that when the machine was operated near its maximum speed, a button might fail to be at the attaching station, when the attaching plunger descended.

The present invention, therefore, contemplates the use of the same form of hopper with its means for orienting the button as it passes from the hopper, but has to do with an improved mechanism whereby the hopper may be continuously rotated by its own motor, so that the chute will always be full of button heads to thus insure that whenever the plunger at the attaching station is operated, a button will be present.

Another object of the invention is to provide a hopper driven by its own motor, which motor, in turn, if so desired, rather than being continuously energized, may be controlled by various electrical control systems, which would permit the rotation of the hopper during a button-attaching operation and for four or five seconds thereafter, which would also insure a ready supply of buttons in the chute.

However, the control system is not shown and forms no part of the present invention.

A further object of the invention is to provide an orienting mechanism wherein the hopper is to be continuously rotated as long as the machine is running, so that the feeding of the buttons from the hopper is not controlled by an intermittent motion synchronized with the plunger, but by a continuous rotative movement of the hopper, thus assuring a full chute of button heads and feed supply for the attaching station at all times.

A still further object of the invention is to provide a central shaft, on which the hopper is

rotated, which shaft has incorporated therewith an over-running clutch, so that when the machine is first started, the operator may, by hand, rotate the hopper several turns or spin the same even when the machine is running. This may be done without in any way affecting the mechanical rotation of the hopper.

Still another object of the invention is to provide a button-attaching machine with a continuously rotated hopper and to arrange an auxiliary power means directly in back of the hopper and carried by the base plate thereof so that the machine does not occupy any more space than it did when operated in a step-by-step manner.

Still another object of the invention is to dispense with the mechanism for providing an intermittent movement to the hopper and to substitute means for a continuous rotative movement of the hopper, and further provide means so that if any buttons are liberated beyond their normal place of escape, they will not jam or be permitted to pass into the chute but, on the other hand, will be carried back to the hopper to be again oriented.

With these and other objects in view, the invention consists in certain new and novel features and combination of parts, as will be hereinafter more fully explained and pointed out in the claims.

Referring now to the drawings showing a preferred embodiment of my invention:

Fig. 1 is a fragmentary top plan view of a button-attaching machine showing the rotative hopper and a fragmentary upper portion of the button chute;

Fig. 2 is a rear view of the same showing the manner of mounting the motor and its gear train for continuously driving the hopper;

Fig. 3 is a side elevation, on a reduced scale, of the hopper and showing the motor for driving the hopper;

Fig. 4 is an enlarged sectional view taken on the line 4—4 of Fig. 2, showing the manner of mounting the hopper and its over-running clutch;

Fig. 5 is a sectional view taken on the line 5—5 of Fig. 4;

Fig. 6 is a sectional view taken on the line 6—6 of Fig. 4;

Fig. 7 is a fragmentary sectional view taken on the line 7—7 of Fig. 1, looking in the direction of the arrows and showing a button about to pass from the hopper;

Fig. 8 is a sectional view taken on the line 8—8

of Fig. 1 and showing a button within the raceway of the hopper;

Fig. 9 is a bottom plan view of an orientable button;

Fig. 10 is a top plan view of the button showing the insignia bearing a definite relation to the flats of the hub; and

Fig. 11 is a side elevation of the button showing one flat and a step or aligning wall for the button.

Referring now to the drawings, and for the moment to Fig. 1, there is shown the hopper and a fragmentary part of the feed chute of a button-attaching machine of the type set forth in the patent granted to me on March 14, 1933, and bearing Number 1,901,375, and in the patent to Franklin R. White, Number 1,901,386, of March 14, 1933.

Furthermore, the present application is a continuation in part of one filed by me on December 12, 1938, Serial Number 245,278, for Orienting button-attaching machine, in that instance the hopper being rotated in a step-by-step movement.

Only that much of the button-attaching machine and its hopper are shown as thought necessary to illustrate the present invention.

Briefly, the improvements in the present construction over the parent case are (1) to make the machine capable of rotating the hopper in a continuous movement rather than in a step-by-step movement; (2) to provide a different form of main supporting and actuating shaft for the hopper, on which is provided an over-running clutch; (3) to provide a motor with a gear train for cooperating with the supporting and actuating shaft above-mentioned; (4) to provide an enlarged raceway adjacent the hopper for the buttons that happen to be carried up the raceway instead of immediately going down the raceway to the feed chute on their way to the attaching station, which enlarged raceway prevents the buttons from having their hubs jammed between the revolving hopper and the base plate of the hopper; (5) to provide means for preventing the buttons that are carried into the enlarged raceway and which are thus no longer in an oriented position, from returning to the feed chute before being again oriented.

In Fig. 1, there will be seen a fragmentary portion 1 of an arm, to which is secured the extending portion 2 of the circular base plate 3, on which is mounted the cup or hopper 4 for holding the buttons that are to be oriented and then attached to the work garments, overalls, or other articles of a similar nature. The base plate 3, in reality, forms the bottom of the cup, and it is between this base plate and the under edge of the hopper (through grooves) that the buttons pass when in their properly oriented position into the raceway 5 with its overhanging wall 46, which raceway is concentric to the cup 4 for a portion of its length, and registers at its one end with the chute 5', which extends tangentially to the cup and then down to the attaching station.

Although it is not shown, it will be understood that this chute extends down to cup-shaped receiving jaws over the attaching station, the button being inverted as it passes down the chute to the cup-shaped receiving jaws, where it is then forced onto a tack by a plunger, which is the usual operation and illustrated in the companion application.

The upper end of the raceway 5 formed in the

base plate, as shown in Fig. 1, is widened, as at 6 by discontinuing the overhanging wall 46, so that if any buttons, in passing from the hopper, as will be later mentioned, contact with the revolving side of the hopper and are carried by friction above a horizontal line drawn through the axis of the cup, they will not become jammed but will pass into the widened portion 6 and in time be carried by friction to the top of the hopper, as at 7, and then drop from this widened portion of the chute into the pocket 8 formed in the base plate and fall into the hopper to be again revolved and oriented.

As will be understood from the parental case, the raceway 5 is open on its inner side and the wall of the hopper, in reality, forms the inside wall of the raceway. Also, the distance between the stationary wall and side wall of the hopper is slightly less than the major diameter of the hub of the button but slightly greater than the width measured on the minor axis of the hub, that is, across the flats. Therefore, as the button passes out of its groove, it is turned in a clockwise direction, due to the friction of the button on the bottom plate and against the outer wall 46 of the raceway and the movement of the rotating hopper, until the flats are parallel with the side wall 46 of the raceway.

The rotation of the hopper, as heretofore mentioned, acting on the buttons not only tends to partially rotate them but tends to elevate them. Then, with a multiplicity of buttons in the raceway, additional buttons coming in, and other buttons being turned, they may have a tendency to jam when reaching a point above the horizontal line, as heretofore mentioned. However, by forming the widened portion so that these buttons may be fully revolved and carried back to the hopper, this tendency of jamming is overcome.

A stop or gate 9 is provided, which consists of the plate 10, secured to the upper edge of the base plate and at a point in a horizontal line drawn through the axis of the cup and has the downwardly extending coil spring 11 that projects into the raceway 5 (Fig. 4), thus preventing any buttons trapped in the widened portion 6 from passing down into the chute 5'. This is a necessary detent, as any buttons in the widened portion 6 are no longer in their oriented position.

Referring now for the moment to Figs. 3 and 4, and particularly to the supporting and actuating shaft for the hopper or cup 4, it will be seen that the base plate 3 is provided with an enlarged hub 12, in which is rotatably mounted the shaft 13. This shaft 13 is provided with a collar 14, that rests on the face of the base plate 3, while about the shaft above the collar 14 may be seen the sleeve 15. Threaded in the sleeve near the lower end thereof may be seen a cross pin 16, which is to engage the walls of a slot 17 formed in the lower end of the hollow hub 18 of the hopper or cup 4.

Referring for the moment to the hopper or cup, it will be seen that from the hub 18 extend the spider arms 19 to the inner side walls of the hopper cylinder, the inner side walls being ribbed vertically, as at 20, so that as the hopper is revolved, the buttons will be continuously tumbled and they will eventually be in a position to pass through the grooves 21 formed in the lower edge of the circular wall of the hopper, as will be shortly mentioned.

At the upper end of the shaft 13, there are the threads 22, about which is threaded the cap

23, while extending between the under surface of the cap and the top of the sleeve 15 is a spring 24, which bears against the steel washer 15', which latter is keyed or locked to the upper end of the shaft 13. Beneath the steel washer 15' is fitted the fiber or composition washer, which bears against the upper end of the sleeve 15. Thus, the sleeve 15 is frictionally held on the shaft 13 and between the washer 15'' and the lower collar 14.

The sleeve 15 is provided with a circumferential groove 25, so that a latch member 26 on the hopper (Fig. 1) may be snapped into and out of this groove, thus locking the hopper on the sleeve until the latch 26 is operated, after which the hopper 4 may be removed from its shaft 13. The cross pin 16 (which, as before mentioned, is threaded in the sleeve) fitting within the slot 17 in the bottom of the hopper hub locks the hopper with relation to the shaft 13, so that any rotative movement imparted to the shaft will be transmitted to the hopper.

The lower end of the shaft 13 is threaded, as at 27, on a reduced diameter, and there is a further reduction in diameter, as at 28, and finally the threads 29 at the extreme end of the shaft.

Locked on the threads 27 is what I term the cam plate 30 of the over-running clutch, which may be seen in detail in Fig. 6. The cam plate 30 is grooved diametrically to form a channel having the opposite vertical walls 32. This channel is also milled opposite the respective vertical walls 32 to form the inclined cam surfaces 31, the walls 32, of course, being the active or driving faces of the cam.

Loosely mounted on the reduced portion 28 of the lower end of the shaft 13 is the driving member 33 of the clutch with its external gear teeth 34 and its two spring-pressed driving pins 35, which pins normally extend beyond the upper surface of the driving member 33 to engage the vertical walls 32 of the cams 31. There is a cover plate 36 extending over the springs of the spring-pressed pins, which cover plate is held in position by the two screws 37. Beyond this (Fig. 4) is the washer 38, which is held in place by the nut 39 on the threaded end 29 of the shaft 13.

Thus, a rotation of the drive plate 33, through the driving pins 35 engaging the vertical walls 32 of the cam groove, will rotate the shaft 13 to, in turn, through the pin 16, rotate the hopper 4.

Also, the hopper may be rotated by hand, that is, over-run the clutch, as the cam surfaces 31 will depress the drive pins within their sockets and thus permit the plate 30 to turn relative to the pins 35.

This over-running clutch, therefore, permits the hopper to be given a few preliminary turns before the machine is started to fill up the feed chute 5' with oriented buttons, and also permits the operator at any time, even through the motor, shortly to be mentioned, is running, to give a few additional twists to the hopper if he notices that the feed chute for any reason is getting low in its supply of buttons.

Now, to drive the hopper in a continuous manner, there may be seen in Fig. 2 the motor 40, which is held to the rear of the hopper plate by the cap screws 41. This motor is provided with a reduction gearing with its driving pinion 42, which meshes with the teeth 34 formed on the drive plate 33 of the over-running clutch. An electric control system (not shown) will be connected with the machine, so that the hopper may be either continuously rotated or the control sys-

tem may be so arranged that it will start the motor when the treadle (not shown) is depressed to attach a button, and this control system will keep the motor energized for a predetermined length of time, say from two to six seconds, after the treadle is released, which will also assure a full supply of buttons in the chute. However, as above-mentioned, the electrical control system or switches are not shown, as they do not 10 per se form any part of the present invention.

In Figs. 7 to 11, inclusive, I have shown the details of the type of button to be oriented and also fragmentarily shown a section of the lower edge of the cup or hopper 4 and the raceway 15 5 to illustrate how the buttons with the particularly shaped hubs may pass from the hopper to the raceway and down the feed chute 5' to the attaching station.

Referring now for the moment to Fig. 7, 20 there is shown a fragmentary section taken on the line 7—7 of Fig. 1, illustrating the grooves 21, which have the step 44 on their one side, so that the button 45 and its hub, when in one rotated position only, may pass through a groove 21 and out into the raceway 5. The circular base plate 3, it might be mentioned here, has the upstanding peripheral wall 3', which normally holds the buttons from passing from the hopper through the grooves until the buttons 30 are opposite the raceway 5.

In Fig. 8, the button 45 is shown as having passed through the groove 21 in its oriented position into the raceway 5 and is now in position to pass down the chute 5' in only one 35 position. It will be understood that the raceway 5 at its lower end and the chute 5' have the overhanging opposite walls 46 contacting with the flats of the hub that prevent the button from turning or revolving as it passes down the 40 raceway and into the chute to its attaching station.

The button 45 forms the subject-matter of 45 separate applications, to wit, one filed by Frederick H. Peterson and Rollin R. Clarke on January 3, 1939, Serial Number 249,135, now Patent Number 2,170,091, granted August 22, 1939, for Tack buttons, and one filed by Frederick H. Peterson and Rollin R. Clarke on May 4, 1939, Serial Number 271,766, now Patent Number 50 2,170,092, granted August 22, 1939, for Tack buttons. However, it might be mentioned briefly that the hub has two flats 47 and 48 with the additional step or aligning wall 49 on the end of the hub, so that the button may only pass 55 through the groove 21 when in one position. The face of the button will be provided with insignia 50 bearing a definite relation to these flats, and in the present instance, the flats are at an angle of 20° to the vertical axis of the insignia, as the chute 5' extends at such an angle to a line drawn through the central axis of the hopper to the attaching station. This angle of the flats is slightly different from that shown in the two patents above-mentioned.

60 It is to be remembered that each button passes from the hopper and down the chute with the hub extending upwardly, but the chute is provided with a twist, so that on reaching the attaching station, the face will be up and the hub will extend downwardly.

65 As is well understood, during the attaching operation, the tack will be held beneath the cloth with the point up and the button head will be forced downwardly by the plunger (not 70 shown) to thus force the tack through the cloth

and up into the button head, where it will be deformed to thus rigidly hold the button to its cloth.

The button may be of the solid type or may be of the shell type, just so it is provided with these two flats and aligning wall bearing a definite relation to the insignia, so that it may only pass out in one position to the raceway 1.

As heretofore mentioned, if any buttons should pass through the grooves 21 above the stop 9, they may float or be revolved within the widened portion 6 of the raceway, thus preventing any jamming of the buttons, which might happen if the raceway were not widened. These buttons that once reach the widened portion 6, however, must not be permitted to pass down through the chute 5', because they are no longer in an oriented position. The stop 9 prevents this and they will either remain in the widened portion 6 or be finally carried up the raceway until they pass into the pocket 8 and down again into the hopper to be tumbled and revolved until once more they are oriented and pass into the raceway 5 and chute 5'.

From the foregoing, it will be seen that I have provided a feeding and orienting means for the buttons, which will always insure a sufficient supply of buttons for the machine, so that there is no danger of the plunger descending to mutilate the tack in the clothe without having its cooperating button head.

Furthermore, the machine is so arranged that the buttons are not likely to jam in the raceway 5 and if they once get out of their oriented position, they are effectively held from entering the chute 5 until they again pass through the radial grooves 21 in the hopper.

Finally, the hopper may be turned by hand either when starting the machine or at any time the hopper is being driven by the motor, thus further assuring a bountiful supply of button heads for the attaching operation.

Many slight changes are possible in the construction hereinbefore set forth without departing from the spirit and scope of the invention.

Having thus described my invention, what I claim as new and desire to secure by Letters Patent is:

A hopper and chute unit for a button-attaching machine including a base plate having an extension portion which latter is adapted to be secured to a supporting arm of a button-attaching machine, a rotatable hopper mounted on the base plate, means secured to the base plate for driving the same, the said base plate being also provided with a concentric wall adjacent a part of the periphery of the hopper and forming a raceway for the buttons liberated from the hopper and having an overhanging portion adapted to contact with flats formed on the hubs of the buttons to prevent them from rotating about their central axes, the overhanging portion of the wall of said raceway extending to a point slightly above a horizontal line drawn through the central axis of the hopper, the remaining portion of the raceway extending to a point near the top of the hopper where the buttons are free to drop back into the hopper, a flexible stop secured to the concentric wall of the raceway and extending therein and located at a point just above where the overhanging portion 35 of the raceway begins, the portion of the raceway without the overhanging wall preventing jams of buttons in the raceway by permitting offending buttons to move up past said stop into said portion where they may rotate about their vertical axes, and the stop means preventing buttons which have passed into said portion from dropping down again into the said raceway.

FREDERICK H. PETERSON.
